HEARSE WITH FLOOR EXTENSION

Ford W. Harris, Los Angeles, Calif., assignor to
 Big Rock Ranch Company, Los Angeles, Calif.,
 a corporation of California

Application October 30, 1933, Serial No. 695,880

13 Claims. (Cl. 296—16)

My invention relates to side loading hearses and it is embodied in a side loading means for a hearse which enables a casket to be conveniently inserted through the side opening of the body 5 of a hearse.

In the old-fashioned hearses the casket is inserted thereinto through an opening formed in the back end of the body. It is ordinarily impossible because of traffic regulations to park the hearse 10 with the back toward the curbing of the street and consequently the pall-bearers are required to step down from the curbing into the street in order to place a casket into the hearse.

The inconvenience of stepping into the street 15 and the disturbance of the solemn appearance of the ceremony are eliminated in the modern side loading hearses which permit the casket to be inserted through an opening formed in the side of the hearse. These modern side loading hearses 20 have the exterior appearance of a standard limousine automobile.

It is rather inconvenient, and sometimes strenuous, for the front pall-bearers to extend the foot of the casket through the side opening of the hearse 25 and into the interior thereof. The reason for this is that the running board of the hearse prevents the front pall-bearers from standing very close to the side opening and consequently they must lean forward or extend their arms forward so that the 30 foot of the casket will project through the side opening before the casket is rested on the floor of the hearse.

It is an object of my invention to provide a hearse 35 with a floor extension which may be extended outward from the body of the hearse below the side opening and which presents an upper surface at the same level with the upper surface of the floor of the hearse. The floor extension forms a platform or shelf on which the foot of the casket may be rested by the front pall-bearers with 40 convenience and without any strenuous effort.

Another object of my invention is to provide a combination of the character mentioned in the 45 paragraph above in which the floor of the hearse and the floor extension are provided with means for reducing the friction between the casket and the floor of the hearse and casket guiding means operable to guide the casket in a non-rectilinear path as it is slid over the floor of the hearse.

A still further object of my invention is to provide a combination as specified above in which the floor extension projects outwardly from the body of the hearse a distance substantially greater than the width of the running board of the hearse.

It is a further object of my invention to provide

a hearse having a floor extension which may be retained in a retracted position in a cavity below the floor of the hearse and which may be extended outwardly to one side of the body below the side opening and in the same plane as the floor. 5

It is also an object of my invention to provide in a combination of the character specified in the above paragraph: a floor extension which is supported in a cavity below the floor of the hearse, there being guide means upon which the extension 10 is slideable into an extended position; means by which an operator can raise the extension into an upper position in which the extension presents an upper surface in the same plane as the upper surface of the floor of the hearse; and means 15 for clamping the extension in this extended upper position.

These and other objects will be apparent from a perusal of the following part of the specification and the accompanying drawings. 20

Referring to the drawings,

Fig. 1 is a sectional plan view of a side loading hearse embodying the features of my invention.

Fig. 2 is a fragmentary vertical section through a portion of the floor of a hearse and the floor 25 extension of the invention, the floor extension being shown in its retracted position, this view being taken as indicated by the line 2—2 of Fig. 1.

Fig. 3 is a view comparable to Fig. 2 but showing the floor extension in its extended upper 30 position.

Fig. 4 is a vertical section taken as indicated by the line 4—4 of Fig. 2.

Fig. 5 is a fragmentary vertical section taken as indicated by the line 5—5 of Fig. 2. 35

Referring to the drawings and to Fig. 1 in particular, the numeral 11 represents an automobile hearse having a body 12. The body 12 provides an interior compartment 13 having a floor 14, the major axis of which is parallel to 40 the direction of travel of the hearse 11 and the minor axis of which is at right angles to the major axis. One side of the body 12 is provided with a side opening 15, which is usually narrower than the length of the casket carried by the 45 hearse, and for this reason the casket must be longitudinally inserted through the side opening 15 and into the compartment 13. The side opening 15 is provided with hinged side doors 16 normally closing this opening, giving the hearse 11 50 the general appearance of a limousine or sedan.

As best shown in Figs. 2 to 4, inclusive, the side 17 of the body 12 is provided with a cavity 18, directly below the side opening 15, and which is elongated in the direction of the major axis 55

of the body, the upper and lower walls of the cavity being defined respectively by the floor 14 and the upper surface 19 of the frame 20 of the chassis of the hearse 11.

5 Secured to the inner side of the frame 20 adjacent the longitudinal extremities of the cavity 18, as by bolts in the manner shown, is a pair of brackets 21 adapted to serve as supports for a floor extension 22, which is received through 10 the side 17 of the hearse through the cavity 18.

15 The brackets 21 include means for supporting the floor extension in a lower position below the floor 14 of the hearse and means for guiding the floor extension when it is drawn into a laterally extended position, in which position it projects outwardly beyond the floor 14 and beyond the running board of the hearse.

20 The brackets 21 are preferably formed so as to project inwardly toward the major axis of the body 12 a substantial distance as shown, and are provided with horizontally extending surfaces 23, serving as ways upon which skids 24 secured to the bottom surface of the extension 22 are slidably supported. The skids 24 may be conveniently formed of angle iron, the horizontally extending legs 25 thereof being secured to the bottom surface of the extension 22 by screws, as shown, and the vertically extending legs 26 thereof of resting slidably on the ways 23.

25 30 The guiding means above referred to is provided in the form of a plurality of vertically extending fingers 28 formed integrally with the brackets 21 and adapted for slidable engagement with the inner surfaces of the legs 26 of the skids 24, as best shown in Fig. 5. Stop means in the form of inwardly extending ears 30 are provided on the inner ends of the skids 24, these ears being adapted to engage the innermost guide fingers 28, in the manner best shown in Fig. 3, to limit the outward movement of the floor extension 22.

35 40 The inner end of the floor extension 22 is provided with an offset portion 35 providing a vertical shoulder 36 extending entirely across the upper surface of the floor extension at right angles to the direction in which the extension is slidable. It will be noted that the offset portion 35 is offset downwardly a distance substantially equal to the thickness of the floor 14. It will 45 also be noted that the length of the offset portion with relation to the stop ears 30 is such that when the extension 22 is fully extended, the shoulder 36 is in a position to clear the outer edge 37 of the floor 14 when the extension 22 is 50 raised vertically.

55 My invention also provides means for raising the floor extension from its extended lower position in which it is supported by the skids 24 engaging the ways 23, into an extended upper position in which the upper surface 38 of the offset portion 35 is clamped against the lower surface of the floor 14, so that the upper surface 39 of the extension 22 is in the same plane as the upper surface of the floor 14 and is locked in this 60 position.

65 One form of providing this means includes a horizontal shaft 45 rotatably mounted in bearings 46 provided in the brackets 21. As shown, the shaft extends transversely with respect to the ways 23 upon which the extension is slidably and in a plane therebelow. Fixedly mounted on the shaft 45, directly below the horizontal leg 25 of each of the skids, is a clamping member 47. Each of the clamping members 47 includes 70 an outwardly extending arm 48 terminating in

an enlarged head providing a cam surface 49 adapted to engage the leg 25 of the skid 24 thereabove upon a rotational movement of the shaft 45 and lift the extension 22 into its extended upper position, locking the extension in this position by clamping the upper surface 38 of the offset portion against the lower surface of the floor 14 as described above. 5

It will be noted that the cam surfaces 49 provide arcuate surfaces 50 and flat surfaces 51 tangential thereto and perpendicular to the longitudinal axis of the arms 48. When the floor extension 22 is in its lower retracted position the arm 48 of the clamping member 47 rests in a non-vertical position against the frame 18 of the car, 15 or other suitable stop means, so that the cam surfaces 49 are out of contact with the floor extension as shown in Fig. 2, allowing the floor extension to be freely slidable on the ways 23. When the clamping members 47 are swung left- 20 wardly, as viewed in Fig. 2, by a rotation of the shaft 45, the arcuate surfaces 49 engage the legs 25 of the skids 24 camming the extension 22 upwardly into its extended upper position, the guide fingers 28 and the stops 30 cooperating to 25 prevent any lateral twist of the extension so that the shoulder 36 will clear the outer edge 37 of the floor 14 as the extension is raised.

30 It will be noted in Fig. 3 that when the arm 48 of the clamping member 47 is in a vertical position, a vertical force is exerted against the floor extension through the flat perpendicular surface 51, which, due to the relatively enlarged area of this surface, tends to prevent inadvertent rotation of the clamping members 47 from their vertical position, thus securely locking the floor extension 22 in its extended upper position. 35

35 One suitable means for rotating the shaft 45 to accomplish the function of raising the extension from its extended lower position into its extended 40 upper position comprises a lever 55 fixedly mounted on one end of the shaft 45, the handle portion thereof projecting upwardly through an opening 56 provided in the floor 14. The lever 55 is preferably mounted on that end of the shaft 45 toward 45 the forward end of the chassis of the hearse, so that the handle portion thereof projects through the floor 14 forwardly of the side opening 15 and adjacent the driver's seat, as shown in Fig. 1 of the drawings. 50

55 Other operating means for rotating the shaft 45 may, of course, be used if desired, the lever being merely illustrative of one simple form of operating means. So also, the clamping members 47 constitute only one of several equivalent means 55 for raising the extension from its lower to its upper position, and it should be understood that the invention should not be limited to the construction shown.

60 My invention also includes means for reducing the friction between a casket and the floor of the hearse as the casket is slid over the floor by providing roller means 60 and 61 projecting slightly above the upper surfaces of the floor 14 and the floor extension 22 respectively. The roller means 65 60 and 61 are supported in suitable frames 62 preferably set flush with the upper surface of the floor 14.

65 70 The roller means 60 and 61 comprise a means for guiding the casket in a non-rectilinear path as it is slid over the floor 14 into the compartment 13. The function of the rollers 60 and 61 as a guiding means is to support a casket in such a manner that when the casket is slid endwise through the side opening 15, the rollers will auto- 75

5 matically swing the casket into a position parallel to the major axis of the compartment 13. The rollers 60 and 61 are arranged so that their axes radiate from a point indicated at 65 which is located substantially at 45° to the major axis at the rear and to one side of the compartment 13.

When the foot of a casket is rested on the extension 22 it is supported by the rollers 61. When the casket is slid inwardly the foot extends through the side opening 15 and engages the rollers 60. The action of the rollers 60 is to shift the foot of the casket toward the rear end of the compartment 13. As each succeeding roller 60 is engaged by the foot of the casket the direction of travel of the casket is changed, so that when the head of the casket rests on the rollers 60 adjacent the side opening 15, the casket is nearly parallel with the major axis of the compartment and requires little manual effort to shift the head of the casket inwardly so that it is parallel to the major axis. The floor 14 and, if desired, the floor extension 22 may be equipped with ball rollers 63 to assist in reducing the friction between the casket and the floor.

25 In the operation of my invention the floor extension 22 is, of course, normally carried in its retracted position below the floor 14, in which position it is shown in Fig. 2, the outer edge thereof being preferably flush with the side of the hearse so as to be inconspicuous, the hearse presenting the general appearance of an ordinary limousine. When a casket is to be placed in the hearse, the floor extension is manually drawn outward into its fully extended position, limited by the stops 30, and then the operating lever is utilized in the manner above described to raise the extension into its extended upper position and lock it in that position. The extension 22, projecting outwardly beyond the running board of the hearse, allows the pall-bearers at the foot of the casket to stand clear of the running board while placing the casket in the hearse.

Although I have shown and described only one complete embodiment of my invention, it should be understood that I am aware of various changes that might be made, and numerous embodiments thereof that might be devised which would nevertheless come within the true scope of my invention interpreted by the appended claims.

(50) I claim as my invention:

55 1. In a side-loading hearse, the combination of: a body having a doorway in the side thereof; a floor within said body adapted to support a casket by presenting an upper surface upon which the casket may be supported and over which the casket may be slid; an extension adapted to support a portion of said casket projecting beyond said floor and adjacent to said doorway by presenting an upper surface in the same plane as
60 said floor and continuous therewith; guide means adapted to guide said extension to a position below said floor by providing supports by which said extension is supported in a lower position such that it can pass into a cavity below said
65 floor; and locking means adapted to lock said extension in its extended position with the upper surface of said extension in the same plane as the upper surface of said floor and continuous therewith, said function being performed by raising said extension from said lower position to an upper position and locking it in said upper position.
70

2. In a side-loading hearse, the combination of: a body having a doorway in the side thereof; a floor within said body adapted to support a

casket by presenting an upper surface upon which the casket may be supported and over which the casket may be slid; an extension adapted to support a portion of said casket projecting beyond said floor and adjacent to said doorway by presenting an upper surface in the same plane as said floor and continuous therewith; guide means adapted to guide said extension to a position below said floor by providing supports by which said extension is supported in a lower position such that it can pass into a cavity below said floor; a clamping member adapted to lock said extension in its extended position with the upper surface of said extension in the same plane as the upper surface of said floor and continuous therewith by forcing said extension from said lower position into said upper position; and means by which an operator can lock said extension in said extended upper position by actuating said clamping member.

3. In a side-loading hearse, the combination of: a body having a doorway in the side thereof; a floor within said body adapted to support a casket by presenting an upper surface upon which the casket may be supported and over which the casket may be slid; an extension adapted to support a portion of said casket projecting beyond said floor and adjacent to said doorway by presenting an upper surface in the same plane as said floor and continuous therewith; guide means adapted to guide said extension to a position below said floor by providing supports by which said extension is supported in a lower position such that it can pass into a cavity below said floor; means for reducing the friction between said casket and said floor as said casket is slid over said floor by providing roller means between said floor and continuous therewith and said casket; and locking means adapted to lock said extension in its extended position with the upper surface of said extension in the same plane as the upper surface of said floor, said function being performed by raising said extension from said lower position to an upper position and locking it in said upper position. 25 30 35 40 45

4. In a side-loading hearse, the combination of: a body having a doorway in the side thereof; a floor within said body adapted to support a casket by presenting an upper surface upon which the casket may be supported and over which the casket may be slid; an extension adapted to support a portion of said casket projecting beyond said floor and adjacent to said doorway by presenting an upper surface in the same plane as said floor and continuous therewith; guide means adapted to guide said extension to a position below said floor by providing supports by which said extension is supported in a lower position such that it can pass into a cavity below said floor; means for reducing the friction between said casket and said floor as said casket is slid over said floor by providing roller means between said floor and said casket; a clamping member adapted to lock said extension in its extended position with the upper surface of said extension in the same plane as the upper surface of said floor and continuous therewith by forcing said extension from said lower position into said upper position, and means by which an operator can lock said extension in said extended upper position by actuating said clamping member. 50 55 60 65 70

5. In a side-loading hearse, the combination of: a body having a doorway in the side thereof; a floor within said body adapted to support a casket by presenting an upper surface upon which the 75

casket may be supported and over which the casket may be slid; an extension adapted to support a portion of said casket projecting beyond said floor and adjacent to said doorway by presenting an upper surface in the same plane as said floor and continuous therewith; guide means adapted to guide said extension to a position below said floor by providing supports by which said extension is supported in a lower position such that it can pass into a cavity below said floor; means for causing said casket to move over a non-rectilinear path as it is slid over said floor by providing suitable casket guiding means in said floor; and locking means adapted to lock said extension in its extended position with the upper surface of said extension in the same plane as the upper surface of said floor and continuous therewith, said function being performed by raising said extension from said lower position to an upper position and locking it in said upper position.

6. In a side-loading hearse, the combination of: a body having a doorway in the side thereof; a floor within said body adapted to support a casket by presenting an upper surface upon which the casket may be supported and over which the casket may be slid; an extension adapted to support a portion of said casket projecting beyond said floor and adjacent to said doorway by presenting an upper surface in the same plane as said floor and continuous therewith; guide means adapted to guide said extension to a position below said floor by providing supports by which said extension is supported in a lower position such that it can pass into a cavity below said floor; means for causing said casket to move over a non-rectilinear path as it is slid over said floor by providing suitable casket guiding means in said floor; a clamping member adapted to lock said extension in its extended position with the upper surface of said extension in the same plane as the upper surface of said floor and continuous therewith by forcing said extension from said lower position into said upper position; and means by which an operator can lock said extension in said extended upper position by actuating said clamping member.

7. In a side-loading hearse, the combination of: a body having a doorway in the side thereof; a floor extension adapted to support a portion of a casket projecting beyond the floor and adjacent said doorway of the hearse by providing an upper surface on said extension in the same plane as the upper surface of said floor and continuous therewith; and means by which an operator can secure said extension in its extended position by clamping said extension so that it cannot move with relation to said floor.

8. In a side-loading hearse, the combination of: a body having a doorway in the side thereof; a floor in said body adapted to support a casket by presenting an upper surface upon which the casket may be supported and over which the casket may be moved; an extension adapted to be retracted normally in a cavity located beneath said floor and movable to an extended position in which it extends beyond the side of said body adjacent to said doorway; a transverse bar positioned beneath said cavity; elevating means associated with said bar and adapted to raise said extension when said extension is in said extended position to a raised position in which the upper surface of said extension is in the same plane as said upper surface of said floor and continuous therewith; and actuating means for actuating said bar so as to cause said extension to said raised position and to lock said extension in said raised position.

said bar so as to cause said elevating means to raise said extension to said raised position and to lock said extension in said raised position.

9. In a side-loading hearse, the combination of: a body having a doorway in the side thereof; a floor in said body adapted to support a casket by presenting an upper surface upon which the casket may be supported and over which the casket may be moved; an extension adapted to be retracted normally in a cavity located beneath said floor and movable to an extended position in which it extends beyond the side of said body adjacent to said doorway; a transverse bar positioned beneath said cavity; elevating means associated with said bar and adapted to raise said extension when said extension is in said extended position to a raised position in which the upper surface of said extension is in the same plane as said upper surface of said floor and continuous therewith, said elevating means being normally out of contact with said extension; and actuating means for actuating said bar so as to cause said elevating means to engage and to raise said extension to said raised position and to lock said extension in said raised position.

10. In a side-loading hearse, the combination of: a body having a doorway in the side thereof; a floor in said body adapted to support a casket by presenting an upper surface upon which the casket may be supported and over which the casket may be moved; an extension adapted to be retracted normally in a cavity located beneath said floor and movable to an extended position in which it extends beyond the side of said body adjacent to said doorway; a transverse bar positioned beneath said cavity; elevating means associated with said bar and adapted to raise said extension when said extension is in said extended position to a raised position in which the upper surface of said extension is in the same plane as said upper surface of said floor and continuous therewith; and actuating means for actuating said bar so as to cause said elevating means to raise said extension to said raised position and to lock said extension in said raised position, said actuating means being operable from a point above said floor.

11. In a side-loading hearse, the combination of: a body having a doorway in the side thereof; a floor in said body adapted to support a casket by presenting an upper surface upon which the casket may be supported and over which the casket may be moved; an extension adapted to be retracted normally in a cavity located beneath said floor and movable to an extended position in which it extends beyond the side of said body adjacent to said doorway; a transverse bar positioned beneath said cavity; cam means associated with said bar and adapted to raise said extension when said extension is in said extended position to a raised position in which the upper surface of said extension is in the same plane as said upper surface of said floor and continuous therewith; and actuating means for actuating said bar so as to cause said cam means to raise said extension to said raised position and to lock said extension in said raised position.

12. In a side-loading hearse, the combination of: a body having a doorway in the side thereof; a floor in said body adapted to support a casket by presenting an upper surface upon which the casket may be supported and over which the casket may be moved; an extension adapted to

- be retracted normally beneath said floor and movable to an extended position in which it extends beyond the side of said body adjacent to said doorway; and elevating means within said body and operative therein to raise said extension when in extended position to a raised position in which the upper surface of said extension is in the same plane as said upper surface of said floor and continuous therewith.
- 5 10 13. In a side-loading hearse, the combination of: a body having a doorway in the side thereof; a floor in said body adapted to support a casket by presenting an upper surface upon which the casket may be supported and over which the

casket may be moved; an extension adapted to be retracted normally beneath said floor and movable to an extended position in which it extends beyond the side of said body adjacent to said doorway; and elevating means within said body and operative therein to raise said extension when in extended position to a raised position in which the upper surface of said extension is in the same plane as said upper surface of said floor and continuous therewith, said elevating means being adapted to lock said extension in said raised position.

10

FORD W. HARRIS.

CERTIFICATE OF CORRECTION.

Patent No. 2,007,425.

July 9, 1935.

FORD W. HARRIS.

It is hereby certified that error appears in the printed specification of the above numbered patent requiring correction as follows: Page 3, second column, line 38, claim 3, strike out the words "and continuous therewith" and insert the same after "floor" in line 42, of said claim; and that the said Letters Patent should be read with this correction therein that the same may conform to the record of the case in the Patent Office.

Signed and sealed this 27th day of August, A. D. 1935.

Leslie Frazer

Acting Commissioner of Patents.
